DESIGN FOR AN AUTOMOBILE LAMP SUPPORT BRACKET

Sol H. Lapidus, Brooklyn, N. Y.

Application September 1, 1948, Serial No. 148,410

Term of patent 14 years

(Cl. D48—32)

To all whom it may concern:

Be it known that I, Sol H. Lapidus, a citizen of the United States, residing at the Borough of Brooklyn, in the county of Kings and State of New York, have invented a new, original, and ornamental Design for an Automobile Lamp Support Bracket, of which the following is a specification, reference being had to the accompanying drawing, forming part thereof.

In the drawing

Fig. 1 is a front view of an automobile lamp support bracket, showing my new design;

Fig. 2 is a side elevation thereof;

Fig. 3 is a bottom view thereof; and

Fig. 4 is a rear elevation thereof.

The dot-and-dash lines in the drawings are for illustrative purposes only.

I claim:

The ornamental design for an automobile lamp support bracket, as shown and described.

SOL H. LAPIDUS.
